NECKTIE

Jean L. Sharkey, Los Angeles, Calif.

Application August 9, 1948, Serial No. 43,340

8 Claims. (Cl. 2—152)

1

My invention relates to and has for a purpose the provision of a necktie which can, without requiring any particular skill, be manipulated to produce the appearance of a four in hand necktie or an ascot tie, or a modified form of an ascot necktie, and all without the tedious process of actually tying the ties as with the conventional ties. Thus, a necktie capable of assuming these various forms is usable in any one thereof as the wearer may select or in keeping with his particular style of shirt or dress.

It is also a purpose of my invention to provide a necktie which not only is susceptible of assuming the different forms described, but greatly reduces the amount of material necessary to its construction, as it is not made to extend around the neck of the wearer as is the conventional tie, but is quickly and easily attachable to the neck of the shirt beneath and at the front of the collar. Additionally, it can be as easily detached as it can be attached, and both operations can be performed without disturbing the form of the tie.

I will describe only one form of necktie embodying my invention, and will then point out the novel features thereof in claims.

In the accompanying drawings:

Fig. 1 is a view showing in front elevation my necktie in the form simulating an ascot tie, and applied to a shirt and collar.

Fig. 2 is a view similar to Fig. 1 showing another form which my necktie may assume.

Fig. 3 is a view similar to Fig. 2 showing the necktie in the form simulating that of a four-in-hand tie.

Fig. 4 is a view on an enlarged scale showing the necktie in the form illustrated in Fig. 3, but in rear elevation.

Fig. 5 is a fragmentary view showing the necktie in front elevation and with the flap thereof extended to show the front side thereof.

Fig. 6 is a view showing the necktie in rear elevation and with the flap to the rear side of the body of the necktie.

Fig. 7 is an enlarged vertical sectional view taken on the line 7—7 of Fig. 6.

Fig. 8 is a view similar to Fig. 7 but showing the flap extended to the forward side of the necktie in the normal position which it assumes when worn.

Fig. 9 is an enlarged sectional view taken on the line 9—9 of Fig. 6.

My invention comprises a body B or skirt and flap F, both of which are made of any suitable necktie fabric and provided on their unexposed sides with suitable linings 15 and 16, respectively, stitched at their edges to the edges of the two pieces of fabric. The body or skirt B is elongated, slightly tapered, and normally of considerable width in respect to its length. Its lower or wide end 17 is shaped in the form of a conventional necktie, while its upper end has a linear transverse edge 18.

2

The flap F has an upper straight edge 19, side edges tapered as at 20 for a portion of their length and then converging as at 21 for the remainder of their length, and to a point 22. While I have described a specific shape of flap, it will be understood that such shape while desirable is not necessary, and, hence, may be varied so long as the flap performs the functions intended as will be later described herein.

The manner in which the flap F is associated with the body B is best illustrated in Figs. 7 and 8, wherein it will be seen that the upper edge 19 of both lining 16 and flap F are secured to the lining 15 and to the body B by a transverse line of stitching 23, and at a point spaced from the upper edge 18 of the body B. Also, at a point spaced from the edge 19 of the flap the lining 16 is secured to the flap by stitching along a transverse line 24, and in such manner as to give fullness to the lining so that it cooperates with the flap to form a transverse sleeve 25.

The sleeve 25 is provided for the purpose of receiving a strip 26 preferably of elastic material so that it may be stretched lengthwise. The opposite ends of the strip project from the ends of the sleeve and in these ends are secured eyes 27 of wire hooks 28 having pointed free ends 29. These hooks 28 constitute elements for attaching the flap F to the neck portion of a shirt as will be described hereinafter, and it will be understood that other attaching elements than these may be employed without departing from the spirit of my invention.

As shown in Fig. 6, the rear side of the flap F, that is, the lining side, has secured thereto so that they are not exposed at the front side of the flap, the two parts 30 and 31 of a conventional snap fastener. These parts 30 and 31 are preferably secured to the two corners of the flap formed at the junction of the divergent and convergent edges 20 and 21 in order that when the two parts are engaged one with the other as illustrated in Fig. 4, the flap will assume the form of a four-in-hand tie knot.

In the use of my necktie, the flap F is swung from the rear side of the body B as shown in Fig. 7 over the upper edge 18 of the body and to the front side thereof as shown in Fig. 8. The flap F occupies this position in all the forms which the necktie is adapted to assume as applied to a shirt collar. The necktie is applied to a shirt having an attached collar by extending the upper end of the tie beneath the collar, and manipulating the attaching elements 28 so that the pointed ends 29 pierce the shirt material and thus hold the necktie suspended from the collar. It will be understood that the elastic strip 26 affords a spacing adjustment of the elements 28 such that when they are in engagement with the shirt the strip is under tension to prevent disengagement of the hooks from the shirt.

My necktie assumes the general form of an ascot tie when applied with the body B fully ex-

tended transversely and the flap F fully extended vertically, as illustrated in Fig. 1. If it is desired that the necktie assume a modified form of ascot the longitudinal edges of the body B can be folded inwardly, as indicated in dash lines in Fig. 2, so that the width of the body corresponds substantially to the width of the flap.

Should it be desired to have the necktie assume the general contour of the conventional four-in-hand necktie, it is necessary that the tip or pointed end of the flap be folded upwardly as indicated in dash lines in Fig. 3, whereupon, the side edges of the flap are folded around the body B to bring the parts 30 and 31 of the snap fastener into engagement with each other so as to secure the flap in this form. As a result of so manipulating the flap it is given the form of the knot of a conventional four-in-hand, and the body B is gathered or constricted within the flap to give a tapered form to the body where it extends downwardly from the flap. Thus, in this manner my necktie is caused to assume the appearance of a conventional four-in-hand necktie.

Manifestly, a necktie constructed in accordance with my invention can be easily manipulated to assume the various forms described, and in all forms it can be readily attached beneath the collar of a shirt and firmly held in fixed position with relation to the collar. Also, it may be readily detached from the shirt, and without losing its form, so that when reapplied it has the same form. Additionally, a necktie so constructed uses a relatively small quantity of material as against the conventional ascot or four-in-hand necktie, as it eliminates the material necessary to tie a knot, and also the material that extends around the neck of the wearer as with the conventional four-in-hand necktie.

Although I have herein shown and described only one form of necktie embodying my invention, it is to be understood that various changes and modifications may be made therein without departing from the spirit of my invention and the spirit and scope of the appended claims.

What I claim is:

1. A necktie having an elongated body increasing in width from a linear end to a pointed end; a flap increasing in width from the linear end toward the pointed end; a lining for the flap of the same contour and size as the flap, the flap and the lining secured to the back of the body at the linear edge thereof along their linear edges, and secured to each other along a line spaced from their linear edges to form a sleeve at the back of the body, the flap and lining being extendable from the back side of the body over the linear edge thereof to the front side of the body to cause the flap to coact with the body in simulating an ascot tie; and means extending through the sleeve for mounting the body and flap beneath a shirt collar.

2. A necktie convertible to simulate either an Ascot tie or a four-in-hand tie, including a tapered body; a flap secured at one end to the narrow end of the body so as to be pendant therefrom at the forward side of the latter and having a synclinal lower edge to simulate an Ascot tie knot; fasteners on the rear side of the flap for holding the flap folded around the body to simulate the knot of a four-in-hand tie; and shirt engaging means for suspending the flap and the body substantially from the collar portion of a shirt.

3. A necktie having a tapered body; a flap;

means for securing the flap to the rear side of the body at the narrow end thereof so that it may be swung over said end to the forward side of the body; fastening means carried by the flap for attaching the latter to a shirt when at the forward side of the body; and fasteners on the rear side of the flap for securing it in folded condition about the body.

4. A necktie having an elongated tapered body; a flap secured at one end to the narrow end of the body so as to overlie the latter with its side edges free of the body; fasteners on the rear side of the flap for holding it in folded condition around the body to simulate the knot of a four-in-hand tie; and shirt engaging means in proximity to the secured end of the flap for suspending the flap and the body substantially from the collar portion of a shirt.

5. A necktie having an elongated body; a flap of less length than that of the body, secured substantially at its upper end to substantially the upper end of the body and overlying the front of the latter; and means connected to the flap end of the body for attaching it to the front of a shirt beneath the collar thereof; said means including a sleeve in proximity to the upper end of the flap; a member within said sleeve and shirt engaging elements on the ends of the member.

6. A necktie having an elongated body; a flap of less length than that of the body, secured substantially at its upper end to substantially the upper end of the body and overlying the front of the latter; and means connected to the flap end of the body for attaching it to the front of the shirt beneath the collar thereof; said means including a sleeve at substantially the junction of the body and the flap; an elastic member within said sleeve; and shirt engaging elements on the ends of said member in the form of pointed hooks.

7. A necktie as embodied in claim 1, wherein coacting fastening elements are secured to the back side of the flap, substantially at its widest point affording means for securing the flap about the body to lend to the tie as a whole the appearance of a four-in-hand tie.

8. A necktie having an elongated tapered body; a flap secured at one end to and depending from the narrow end of said body at the front side thereof and coacting therewith to simulate an Ascot tie; separable fasteners on the flap for detachably holding it in folded position about the body to simulate the knot of a four-in-hand tie; and shirt engaging means secured to the narrow end of said body for suspending the flap and the body from a shirt.
